UNITED STATES PATENT OFFICE.

JOSEPH S. DENNY, OF TARENTUM, PENNSYLVANIA, ASSIGNOR OF ONE-THIRD TO JOHN A. DOOKTOR, OF TARENTUM, PENNSYLVANIA.

LEER.

No. 908,399.

Specification of Letters Patent.

Patented Dec. 29, 1908.

Application filed February 19, 1907. Serial No. 368,244.

To all whom it may concern:

Be it known that I, JOSEPH S. DENNY, a citizen of the United States of America, residing at Tarentum, in the county of Allegheny and State of Pennsylvania, have invented new and useful Improvements in Leers, of which the following is a specification.

This invention relates to improvements in leers or annealing furnaces employed in the art of manufacturing glass ware, the primary object of the invention being to provide an automatic conveyer for maintaining the glass ware in the annealing furnace for treatment a predetermined period of time and then discharging the same on to the delivery apron or device, and to provide feeding and delivery devices designed to convey the glassware by gravity to and from the furnace, thus obviating the necessity of employing power in these operations and as a result reducing the cost of manufacture.

In the accompanying drawings,—Figure 1 is a side elevation of a leer constructed in accordance with my invention, the furnace and conveying mechanism therein being generally indicated. Fig. 2 is a top plan view of the same. Fig. 3 is a detail view showing in side elevation and cross section the construction of the roller supporting rails. Fig. 4 is a sectional elevation looking from the rear toward the operating mechanism of the conveyer, showing the parts in the position they assume just prior to the release of the clutch mechanism to stop the motion of the conveyer. Fig. 5 is a section on line 5—5 of Fig. 4, showing the clutch shifting gearing in inner side elevation. Fig. 6 is a detail section on line 6—6 of Fig. 4. Fig. 7 is a longitudinal section through one of the ends of one of the supporting rollers of the feeding and delivering devices, the section being taken on line 7—7 of Fig. 8. Fig. 8 is an end elevation of the roller. Figs. 9 and 10 are cross sections thereof, taken respectively on the lines 9—9 and 10—10 of Fig. 7.

Referring to the drawings, the numeral 1 generally or conventionally represents the fire box or furnace, 2 the feed mechanism for conveying the glassware thereto, and 3

the delivery mechanism for conveying the treated glassware to the packing houses or other delivery points.

The feed device 2 comprises one or more frames or tables 4 supported upon legs 5 carried by wheels or rollers 6 to enable said table or tables to be moved into and out of position between the furnace and suitable supports 7 carrying the boxes or trays containing glassware to be treated. The delivery mechanism 3 is preferably stationary and has a supporting base of masonry or other suitable material, said device being arranged to convey the treated ware from the furnace to suitable supports 8 in the packing house or at the desired delivery point. The said feeding and delivering devices are inclined downward toward and from the inlet and outlet of the furnace and are provided with transversely arranged supporting rollers 9 adapted to freely turn to permit the trays to slide freely over the same by gravity. The rolls are mounted upon supporting rails 10 formed with notches or open bearings 11 receiving the journals of the rolls. Each roll is hollow or tubular and comprises a cylindrical body 12 closed at each end by a head 13 provided with a central opening 14 and an annular groove 15. Bearings for supporting the end of the roll occupy and project through the opening 14 and comprise inner and outer members 16 and 17, the opposing faces of which are beveled to form cones co-operating with the groove 15 to form a raceway for anti-friction bearing balls 18. A screw shank 19 projects outwardly from the inner member 16, and the member 17 is threaded thereon for adjustment to compensate for wear and is locked in position by a jam nut 20. The projecting portion of the member 17 extends outwardly beyond the head 13 to form a journal for the end of the roll which seats in its receiving recess 11 in the adjacent supporting rail 10. The rolls are thus free to turn upon their bearings, and the trays will thus slide over the rolling surface formed thereby by gravity, thus obviating the necessity of employing the ordinary conveying aprons and dispensing with the use of power to carry the material.

The glassware entering the mouth of the furnace from the feeding device 2 passes onto a traveling apron or belt 21, comprising a pair of side chains 22 connected by transverse rods or bars 23. The chains pass over sprocket wheels 22^a on transverse shafts 24 and 25, and operating means is employed in connection with shaft 25 to intermittently operate said belt, by which the material will be held a determinate length of time in the furnace and then discharged on to the supporting rollers of the delivery device 3.

Keyed to shaft 25 is a pinion 26 meshing with a drive gear 27 loose on a continuously driven shaft 28, which may be operated from any suitable source of power. The gear 27 is limited in sliding movement in one direction by a collar or head 29, and its hub is formed to provide a clutch member 30. The outer side of the clutch member 30 is formed with a tapered recess to receive the tapered portion of a coating clutch member or collar 31 feathered to slide upon and rotate with the shaft, which collar is normally forced away from the clutch member by a coiled spring 32. A sleeve 33 is loose on the shaft and carries pivoted dogs 34 having outwardly curved, beveled or flared short forward ends or arms to normally engage the beveled rear surface of the conical clutch member 31, and having longer rear ends or arms curved, beveled or flared to a greater degree to engage the forward end of a second collar 35 loose on the shaft. Fig. 4 shows the parts moved from their normal position to throw clutch member 31 into engagement with clutch member 30 to lock the gear 27 to the shaft. In the normal or retracted positions of such parts, the forward ends of dogs 34 bear against the rear beveled surface of the cone 31, while the tips of the rear ends of the dogs engage the forward portion of the beveled surface of the sleeve 35, whereby the forward ends of the dogs are spread apart and permit sufficient backward movement of cone 31, under expansion of spring 32, to maintain said cone out of frictional engagement with the clutch face of hub 30. Upon the forward movement of the sleeve 35, the beveled face thereof forces the long arms of the dogs outward, thus causing the beveled short arms thereof to exert pressure upon the beveled face of the cone 31, whereby the latter is forced forward against the resistance of the spring 32 to frictionally engage the hub 30, the short ends of the dogs then moving behind the rear face of the cone, as shown in Fig. 4. The wheel 27 is thus clutched to the shaft 28 to transfer motion to the apron, and it will be observed that the forward movement of the sleeve 35 may be

continued through the yielding action of the dogs, whose forward ends swing in toward the shaft 28, thus allowing the sleeve 35 to have the required range of movement. As the short arms of the dogs not only flare or diverge but have their inner faces beveled, and as the latter bear in the fully projected position of the cone 31 against the rear angular surface of the cone at the intersection of its rear tapered portion and flat rear face, as shown in Fig. 4, it will be understood that such arms tend to swing outward under the pressure of the cone 31 thereon forced backward by the spring 32 as soon as the pressure of the sleeve 35 on the long arms of the dogs is relaxed, the pressure of the spring 32 being amply sufficient to overcome the action of centrifugal force in tending to throw the long arms of the dogs outwardly and the short arms inwardly, which force is, moreover, comparatively slight on account of the comparatively low speed of rotation of shaft 28. Hence, when the sleeve 35 moves rearwardly, or in the reverse direction to that before described, and its pressure on the long arms of the dogs is relaxed, the short arms of the dogs are forced outward by the backward movement of the cone 31 under the action of spring 32, whereby said cone is retracted by the spring 32, thus disengaging the wheel 27 from the shaft 28. The frictional engagement between the parts 31, 33, 34 and 35 may be sufficient to adapt them to rotate in unison, but the resistance of the collar 35 to rotation may be such as to hold the dogs 34 and their supporting sleeve 33 against rotation, in which event the short arms of the dogs will ride in contact with the revolving cone 31. It will thus be seen that through the operation of the dogs by the sleeve 35, the cone 31 will be thrown into and out of engagement with the clutch member 30, thus controlling the action of the gear 27.

The collar 35 is connected with a shifter bar 36 secured to a shaft 37 having a threaded portion 38 on which is a gear nut 39. One end of the shaft 37 is journaled in a rocker bracket 40 pivoted at 41 from a suitable support and having a projecting arm 42. The bracket comprises spaced plates between which the gear nut 39 is arranged, and also arranged between said plates are feed and reversing gears 43 and 44. The gear 43 meshes with the gear 44, which in turn meshes with the gear nut 39, and said gears 43 and 44 are arranged to be alternately thrown by the tilting of the bracket into mesh with a gear wheel 45 fixed in the shaft 28. The bracket plates are connected by the pivot 41, spindles of the gears and a pivot pin 46, which latter is mounted upon the arm 42 and is connected by a link

47 with one end of an intermediately pivoted trip lever 48, the opposite end of which carries a laterally extending finger 49 adapted to be periodically engaged by a trip cam 50 carried by a disk 51 fixed on the shaft 28. A spring 52 operates to hold the free end of the trip lever normally elevated, to depress the link 47 to hold the rocker bracket in the reverse position to that shown in Fig. 5, in which gear 43 will be in mesh with gear 45.

Fig. 4 represents the operative position of the parts of the belt shifting mechanism at the time of the period of release, when the cam 50 has just cleared the trip lever 48 and said lever has been operated by the spring 52 to tilt the bracket from the position shown in Fig. 5 to bring the gear 43 into engagement with gear 45 for the backward movement of the shaft 37 to retract the clutch mechanism. Assuming that the thread 38 is a left-hand thread, and that a tray of ware has just been delivered upon the belt 21 to remain in the furnace a predetermined length of time, it will be understood that the moment the cam 50 moves out of engagement with lever 48, the gear 43 will be thrown into mesh with gear 45, thus transmitting retrograde motion to the gear nut 39 to move the shaft 37 to the right in Fig. 4, whereby the collar 35 will be shifted inwardly, thus effecting the release of the clutch mechanism in an obvious manner to stop the motion of the belt. The time of rest of the belt may vary according to the structure and arrangement of the cam 50, which, at the end of said time, engages the finger 49 and trips the lever 48 against the resistance of spring 52 to throw the gear 44 in mesh with the gear 45, whereby reverse motion will be imparted to shaft 37 to throw the clutch gearing into action, thus fixing the gear 27 to the shaft 28 and transmitting motion to the shaft 25 to start the conveyor 21 for the discharge of the treated material and feed into the furnace of the succeeding tray. When the cam passes the finger the trip mechanism will be operated again by the spring to effect a repetition of the operation above described. It will thus be seen that the material will be fed by gravity to the furnace and discharge by gravity therefrom and will be retained in the furnace a predetermined length of time and then automatically ejected, the operation being such as to secure economy in the treatment of the goods and accuracy in subjecting the same for the proper period to the annealing process.

Having thus described the invention, what is claimed as new, is:

1. In a leir, the combination of a furnace, an endless conveyer therein having a driv-

ing shaft, a continuously driven main driving shaft, gearing between said shafts, including a loose gear, clutch mechanism for throwing said loose gear into and out of action, shifting means for the clutch mechanism driven by the main shaft and including a screw shaft, and trip mechanism actuated by the main shaft for operating said screw shaft in reverse directions.

2. In a leir, the combination of a furnace, an endless conveyer therein having a driving shaft, a continuously driven main driving shaft, gears connecting said shafts, one of said gears being a loose gear, clutch mechanism for throwing said loose gear into and out of action, a screw shaft, a gear nut for actuating said shaft, reversing gearing actuated by the main driving shaft for operating the gear nut, means actuated by the screw shaft for operating the clutch mechanism, and trip mechanism actuated by the main driving shaft for controlling said reversing gear.

3. In a leir, the combination of a furnace, an endless conveyer therein having a driving shaft, a continuously driven main driving shaft, intermeshing gears upon said shafts, the gear upon the main driving shaft being loose thereon, clutch mechanism slidably mounted on said shaft for fixing and releasing the loose gear, a screw shaft for operating the clutch mechanism, a gear nut for actuating the screw shaft, reversing gearing operated by the main driving shaft for turning said nut in reverse directions, and means actuated and controlled by the main driving shaft for shifting said reversing gearing.

4. In a leir, the combination of a furnace, an endless conveyer therein having a driving shaft, a continuously driven main driving shaft, intermeshing gears between said shafts, the gear upon the main shaft being loose, clutch mechanism slidable on said shaft for fixing and releasing said loose gear, a screw shaft movable in opposite directions to control said clutch mechanism, a nut for operating the said shaft, gearing actuated by the main driving shaft for operating the nut, said gearing including pinions for driving the nut in reverse directions, and trip mechanism controlled by the main shaft for alternately rendering said pinions operative to drive the nut in reverse directions.

5. In a leir, a furnace, an endless conveyer therein having a driving shaft, a continuously driven main driving shaft, intermeshing gears upon said shafts, the gear upon the main shaft being loose, sliding clutch mechanism on the main shaft for fixing and releasing the loose gear, a screw shaft for shifting said clutch mechanism, a gear nut for operating said shaft, gearing for actuating

ing the nut comprising a main gear on the main shaft and a pair of pinions adapted to be alternately thrown into and out of mesh with said main gear, one of said pinions being in intermeshing relation with the other and with the gear nut, a rocking support for said nut and pinions, and trip mechanism actuated by the main shaft for rocking said

support in opposite directions at predetermined intervals.

In testimony whereof, I affx my signature in presence of two witnesses.

JOSEPH S. DENNY.
